(57) CLAIM

I claim the ornamental design for a paper towel holder, as shown and described.

DESCRIPTION

FIG. 1 is a perspective view of a paper towel holder of the present design;

FIG. 2 is a top view of the paper towel holder of FIG. 1; FIG. 3 is a front view of the paper towel holder of FIG. 1; FIG. 4 is a right side view of the paper towel holder of FIG. 1; and,
